UNITED STATES PATENT OFFICE.

MICHEL COMPOS, OF MOBILE, ALABAMA.

PRINTING-CONTROLLED ELECTRIC SIGN.

1,092,977.

Specification of Letters Patent. Patented Apr. 14, 1914.

Application filed August 16, 1911. Serial No. 644,348.

To all whom it may concern:

Be it known that I, MICHEL COMPOS, a citizen of the United States of America, and resident of Mobile, in the county of Mobile and State of Alabama, have invented certain new and useful Improvements in Printing-Controlled Electric Signs, of which the following is a specification.

This invention relates to certain new and useful improvements in electric lamp signs, and it pertains more particularly to the means for controlling the display of electric lights in a changeable illuminated sign, advertising plant, announcement-board, bulletin or other device, employing a switch board, with means whereby the said means may be unlimited in its capacity of expression and capable of being operated to immediately produce in the display of lights, any words, letters, or characters, or pictures, as may be desired.

The present invention has for its objects among others to provide a simple, yet efficient and reliable means for controlling the display of the electric lights by a system of printing or the use of letters or other suitable symbols controlled at will by the operator, said letters or other symbols being readily changed as may be desired and when in position controlling, by means of the perforations in the cards, the lighting of the electric lights.

A card is placed in position; the electrical contacts engage the insulation thereof except at points where the perforations are made to form the outline of the letter, picture or other character, and where the contacts enter such perforations they engage the metal plate on which the card or cards may be mounted and complete the circuit, causing the corresponding letters, words, pictures or other characters to be simultaneously displayed on the bulletin, announcement-board, advertisement or other place. I further provide for the cutting out of the display, and by proper connections with a flashing device may flash the display all night, or as long as may be desired.

I aim further at improvements in the details of construction, whereby I am enabled to construct my apparatus at minimum cost and permit of the ready assemblage of parts or their removal for the purpose of repairs, changes or for any other purpose.

Other objects and advantages of the invention will hereinafter appear, and the novel features thereof will be specifically defined by the appended claims.

The invention is capable of embodiment in a variety of forms, and adapted for use in many ways, that herein illustrated being given only as an example of one form but without in any way restricting myself thereto.

The invention, in such preferred form, is clearly illustrated in the accompanying drawings, which, with the numerals of reference marked thereon, form a part of this specification, and in which—

Figure 1 is a top plan of my switchboard or printing plate, with portions broken away. Fig. 2 is a side elevation of Fig. 1. Fig. 3 is a vertical cross section through Fig. 1, as on the line 3—3 thereof. Fig. 4 is an under perspective of one of the controlling plates, removed. Fig. 5 shows in perspective one of the contact selectors, with its parts separated for the purpose of better illustration. Fig. 6 is a perspective view of an apparatus embodying my improvements, showing the announcement-board and the switchboard or printing plate in operative relation. Fig. 7 is a diagrammatic view, showing the circuits, etc.

Like numerals of reference indicate like parts throughout the several views.

In my present construction groups or monograms of lamps are simultaneously operated by a device consisting of parallel series of spring-actuated circuit-selectors arranged to contact with a metallic plate and complete the circuit through correspondingly-arranged circuit-wires, the coacting groups thereof being determined by the perforations in the printing or controlling plate. These plates are placed one at a time in a receptacle or box embracing the groups of circuit-wires, the plate covering all of the circuit wires except those predetermined by the perforations in the controlling plate, according to the letters, words, or pictures or other characters to be displayed, and these are exposed through and by the openings in the plate and permit of the passage of the spring-actuated circuit-selectors to electric contact with the plate when said plate is secured in position, so as to insure operative contact between the selectors and the plate.

through said perforations. The parts are properly insulated so as to insure against short circuiting, and the different elements of the device are capable of manufacture at small cost, and can be readily assembled without skilled labor.

Referring to the drawings 1 designates a board or the like which may be supported upon suitable feet 2, or otherwise, in a horizontal, inclined or other position, as may be found most expedient. In this board are supported the circuit-selectors, which may be of any desired number, running up into the thousands, if necessary. As these circuit-selectors are all alike, a description of one will suffice for all. Attention, therefore, is directed to Figs. 3 and 5, wherein it will be seen that a metal cylindrical, or other shape, body piece 3 is disposed vertically in a suitable opening in the board 1, this body piece being screw threaded at its opposite ends as seen at 4 and 5. Within this body piece is arranged a spring 6, the ends of the body piece extending beyond the upper and lower faces of the board as seen in Fig. 3, the lower end receiving a cap 7, and the other end a cap 8. These caps serve to hold the body piece firmly in the board and permit of ready separation when desired. The cap 8 has a central opening 9 in its outer end through which loosely works the outer end of the contact member 10, the inner end of which is received in the body piece 3 and has a head or enlargement 11 against which one end of the spring 6 bears as shown clearly in Fig. 3. The spring tends normally to project the end of the contact member 10 through the opening 9 in the end of the cap 8. Through the cap 7 there is an opening into which leads one end of a wire 12 the other end of which is connected with the socket of the lamp at the sign where the display is to be made. It is to be understood that one of such wires is connected with each of the circuit-selector devices, as will be apparent from Figs. 3, 6 and 7. The board 1, thus equipped, constitutes the base of the device at the office or other place from which the control of the display is had.

For the purpose of guiding the controller plates, soon to be described, as they are placed in position upon this board, I place upon the upper surface of the board 1 at the corners the corner or angle plates 13 which serve not only as guides for the said plate but also to prevent lateral and longitudinal shifting of the plate after once having been placed in position. These may be of any suitable character and affixed to the upper face of the board in any well known way.

The controlling plate, now to be described, can be arranged in many ways, it may be arranged to slide, it may be hinged, or it may be made to be placed in position and

removed by hand, by being lifted vertically. The latter is herein illustrated. This controlling plate comprises a base 14 of wood or other suitable material of a size calculated to fit within the space inclosed by the corner pieces on the board 1, as seen clearly in Fig. 3, and to the under face of this base 14 is affixed in any well known way a metal plate, preferably brass, 15, the opposite edges of which are turned over as seen at 16 to form opposite guides into which the cards now to be described may be easily slid or placed and easily removed and by which the cards are held against displacement. An insulating strip 17 is secured to the said plate at one end as seen in Fig. 4.

The cards 18 are formed of fiber or other suitable insulating material and are adapted to be fitted in the metal plate within the guides thereof as seen in Figs. 3 and 4. Each card is provided with perforations, according to the letter, figure or character which it is designed to represent and which is to be correspondingly displayed on the sign, bulletin or announcement-board, or other display device. In Fig. 4 there are four of these cards within the plate on the base, and these are perforated to display the word "Hats", it being understood that other cards are differently perforated in accordance with the figure, letter or character which it is designed to display. To this plate 15 is attached a binding post 19 to which is connected the wire 20, as seen in Figs. 1 and 6. This base with its plate and the cards carried thereby, may be held down to its work in any suitable manner. As it is desirable that it be held down with sufficient force to keep the metal plate in contact with the contact members 10 I provide a lever 21 pivoted at one end as at 22 on the board 1, in any suitable manner, as upon a pivot held in the bifurcation of a bracket or upright 23, its other end being provided with a suitable handle 24 and adapted to engage a suitable catch, hook or the like 25 rising from the board 1. A spring plate 26 may further be provided if necessary against which the said lever presses as seen in figures the said spring plate being if desired secured to the under side of the lever as shown at 27. This tends to equalize the pressure. The wires 12 leading from the circuit-selectors are connected each with a lamp socket 28 of the display sign, bulletin or annunciator-board 29, which may be located in any desired place and at all times under the control of the operator at the printing or controlling plate hereinbefore described. All the wires 12 may be arranged in a cable as shown in Fig. 6, or otherwise. Extending from the wires 12 there may be branch wires 30 as seen in Fig. 6, one for each wire, and these branch wires may lead to a flashing device whereby when desired

the printing operation may be discontinued and the display flashed all night or as long as may be desired. It will be understood that the wire 12 from each circuit-selector 5 extends to one terminal of the lamps; the other terminals of the respective lamps are connected to a single circuit 31, which includes a current-generator or source of electrical energy as represented at 32.

33 is a circuit-switch with which the wire 20 from the brass plate 15 leads as seen in Fig. 7 which shows in diagram the circuits etc. This circuit-breaker or switch is designed to be operated before the plate 14 is placed in position to shut off the current until after the controlling plate has been placed in position, so as to avoid flashing. After the controlling plate is in position the switch is turned.

20 The operation will be readily understood from the foregoing description when taken in connection with the annexed drawings, and, briefly stated is as follows: The parts being connected up as seen in Fig. 6, the controlling plate is put in position, containing as many cards as may be necessary and those perforated according to the design to be displayed. The controlling plate is held down to operative position by the lever 21 and its spring and the switch is then turned to turn on the current. Those contact members 10 which are not coincident with the perforations in the cards are engaged with the insulation 17, which covers the surface 25 of the brass plate except where perforated; those contact members 10 which are coincident with the perforations in the cards enter said perforations and coming in contact with the brass plate complete the circuit and 30 the corresponding lamps in the annunciator-board or advertising sign are lighted. Referring to Fig. 7 it will be noted that, beginning at the left, the first and second, the fourth, the sixth, seventh and eighth, and 35 the eleventh contact members 10 are entered in the perforations of the cards, the corresponding lamps at the right of said figure, beginning at the bottom, are shown as lighted. To change a card, the lever 21 is released, after having first turned the switch 33 to shut off the current, the controlling plate is removed and another with different cards put in position, or the same plate may be used by removing the old cards and substituting therefor others with other arrangements of perforations in accordance with the display to be made. When the controlling plate is removed there of course will be no display made on the sign; the same result is 40 attained by the turning of the switch 33 to shut off the current. Then the sign may be used as a flash by means of the branch wires 30 which permit of the running of the sign as a flasher as may be desired.

45 From the above it will be seen that I have

devised a very simple, yet efficient device for the controlling of the display by a printing system, and while the structural embodiment of the invention as hereinbefore disclosed is what I, at the present time, consider preferable, it is evident that the same is subject to changes, variations and modifications without departing from the spirit of the invention or sacrificing any of its advantages; I therefore do not intend to restrict myself to the exact details hereinbefore described and shown, but reserve the right to make such changes, variations and modifications as come properly within the scope of the protection prayed.

What is claimed as new is:—

1. In a device of the character stated, a circuit-selector comprising a body piece, removable caps therefor, a spring actuated member in said body piece and having one 80 end projecting through one of said caps, a controlling plate and a card of insulating material removably supported on said plate and having perforations some of which are adapted to receive some of said circuit-selectors.

2. In a device of the character described, a circuit-selector comprising a body piece, removable caps therefor, and a spring-actuated member in said body piece and having one 85 end projecting through one of said caps, combined with a controlling plate, a support therefor having guides, an insulating strip and a card of insulating material removably held in said guides and having perforations, 90 some of which are adapted to receive some of said circuit-selectors.

3. In a device of the character described, a board provided with a multiplicity of circuit-selectors with spring-actuated contact members, a controlling plate comprising a base, a metallic plate thereon having its edges turned to form guides, an insulating strip at one end of said guides, a perforated member of insulating material held in said 105 guides, vertical members carried by said board and serving as guides for said plate and holding the latter against lateral and longitudinal shifting, a lever pivoted at one end on said board and extending longitudinally thereof, and means for holding the opposite end in its lowermost position.

4. In a device of the character described, a board provided with a multiplicity of circuit-selectors with spring-actuated contact members, a controlling plate comprising a base, a metallic plate thereon having its edges turned to form guides, an insulating strip at one end of said guides, a perforated member of insulating material held in said 110 guides, vertical members carried by said board and serving as guides for said plate and holding the latter against lateral and longitudinal shifting, a lever pivoted at one end on said board and extending longitudinally thereof, and means for holding the opposite end in its lowermost position.

nally thereof, means for holding the opposite end in its lowermost position, and a spring carried by the underside of said lever and extending in the direction of the 5 length thereof and bearing at its ends against said plate to equalize the pressure thereof on the said circuit-selectors.

Signed by me at Washington, D. C., this 16th day of August, 1911.

MICHEL COMPOS.
